(57) CLAIM

The ornamental design for a hooded garment, as shown and described.

DESCRIPTION

FIG. 1 is a perspective view of a hooded garment showing our new design in an in-use configuration with a hood in a down position;

FIG. 2 is a front view thereof;

FIG. 3 is a rear view thereof;

FIG. 4 is a left side view thereof;

FIG. 5 is a right side view thereof.

FIG. 6 is a perspective view of the hooded garment of FIGS. 1-5 showing our new design in an alternative in-use configuration with the hood in an up position;

FIG. 7 is a front view thereof;

FIG. 8 is a rear view thereof;

FIG. 9 is a left side view thereof; and,

FIG. 10 is a right side view thereof.

The broken lines immediately adjacent to the shaded area represent unclaimed boundaries of the design. The contrast in shading in the zipper regions and lower region of the garment represents a contrast in appearance only and does not represent any particular color, material, texture or finish. The broken lines showing the remainder of the hooded garment and the unshaded regions therein are for environmental purposes only and form no part of the claimed design.
